UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

STEAM-BOILER.

1,252,444.

Specification of Letters Patent. Patented Jan. 8, 1918.

Application filed April 7, 1917. Serial No. 160,869.

To all whom it may concern:

Be it known that I, DAVID S. JACOBUS, a citizen of the United States, residing at Jersey City, county of Hudson, and State of New Jersey, have invented certain new and useful Improvements in Steam-Boilers, of which the following is a specification.

My invention relates to steam boilers and more particularly to those of the general Stirling type and will be understood by reference to the accompanying drawings in which Figure 1 is a vertical longitudinal section; Fig. 2 a detail of the dry pipe in the rear steam and water drum; and Figs. 3 and 4 top views of the drums with different arrangements of the steam circulators. Similar reference numerals indicate similar parts in the several views.

The boiler shown comprises three transverse upper steam and water drums, 1, 2 and 3, connected by banks of tubes 4, 5 and 6 to a mud drum 7. I may use a single mud drum as shown, or a series of connected mud drums, and I intend to cover both constructions by the word lower chamber in the claims. The three upper drums must, however, be connected to this chamber whether it is in the form of one drum or several connected drums. The steam spaces of the front and middle steam and water drums are connected by circulators 8, and the steam spaces of the middle and rear steam and water drums are connected by circulators 9. The water spaces of the front and middle drums are connected by circulators 10 which support tiling 11, as shown. In the present form there are no water circulators between the middle and rear steam and water drums.

The baffling shown is that of the standard Stirling boiler, that is, the rear row of tubes of the front bank support a baffle 12 extending upwardly from the mud drum to the upper part of the bank, and a baffle 13 is supported upon the rear row of tubes of the middle bank extending downwardly from the middle steam and water drum. Horizontal shelves 14 extend from the rear wall of the setting toward the rear bank. The boiler may be fired by any suitable furnace. The gases flow upwardly along and among the tubes of the front bank and after crossing the top of said bank flow into the chamber 15, thence in a general downward

direction over and among the tubes of the middle bank, thence upward over the tubes of the rear bank to the outlet 16. If desired, a superheater may be placed in the chamber 15 between the front and middle banks of tubes. In the form shown in Fig. 1, the superheater comprises the boxes 17 and 18 to which the upwardly projecting U-tubes 19 are connected. The boxes are supported in saddles resting upon the cross beam 20 forming part of the structural work of the setting. The tubes 19 are shown as extending substantially parallel with the tubes of the middle bank, their ends being in close proximity to the middle steam and water drum. Clamps 21 secured to the front row of tubes of the middle bank serve as supports for resisting the overturning moment of the superheater.

In the standard Stirling boiler the front and rear steam and water drums are on substantially the same level and below the middle drum, and the main steam outlet is placed on top of the middle drum. In the construction here shown, the rear steam and water drum is set higher than the usual practice and is substantially at as high a level as the middle steam and water drum, and the main steam outlet 22 is placed on the top of the rear drum and leads to the superheater inlet box 17. Experiments have demonstrated that the water level in the rear drum of a standard Stirling boiler, with the steam space in the middle drum interconnected to both the front and rear drums by steam circulating tubes, is higher under certain conditions of operation with a water containing a material amount of elements in solution than it is with a purer water. It is therefore, not only advantageous, but highly important, to raise the rear drum to the level of the middle drum, when the feed water is of such nature that it will lead to high concentrations in the water contained in the boiler.

A feed pipe 23 enters the rear drum 3 and discharges into a trough 3' which distributes the feed water from end to end of the drum. This use of the trough for distributing the water causes a general cooling of the water in the rear bank of tubes from end to end of the drum. The introduction of the feed water into the rear steam and water drum serves an important function in cooling the

water in the rear drum and the rear bank of tubes, thereby causing the water level in the rear drum to be lower than it would be if not so cooled, and lower than the water level in the middle and front drums, such lower water level giving a greater steam space in the rear drum, and this is advantageous in causing drier steam to enter the dry pipe in the upper part of the rear drum. When the boiler is called upon to generate its maximum capacity, the ebullition of the water in the front and middle banks of tubes causes numerous steam bubbles to be formed in the tubes which reduces the density of the mixture of water and contained steam. As the density of the water in the rear bank is nearly constant, on account of the cooling action of the feed water introduced into the rear drum, the water level in the rear drum will fall to such an extent that there will be no water in the rear drum, at high capacities, other than the feed water which flows through it. This leads to a maximum steam space in the rear drum when it is most desired, that is when the boiler is driven at its maximum capacity and when it is most likely to prime.

In the steam space of the rear drum is placed a dry pipe 24, the main steam outlet 30 22 connecting with said pipe at about the center of the latter. The pipe 24 has openings 25 therein near its ends, as shown in Fig. 2. A plate 26 is placed in the rear drum between the ends of the steam circulators 9 and the dry pipe 24 to deflect any water in the steam toward the bottom of the drum.

The steam circulators 9 for ordinary water conditions will be arranged parallel and 40 will run directly from the middle steam and water drum to the rear steam and water drum as indicated in Fig. 3. For water containing impurities which tend to produce foaming and priming, I prefer to arrange 45 the steam circulators 9' as indicated in Fig. 4, that is in two groups, extending from near the ends of the middle steam and water drum to the center of the rear steam and water drum. By so arranging the circulators 9', the steam will be taken from the 50 middle steam and water drum 2 where it is in the most quiescent state in that drum, and will be discharged into the middle portion of the rear steam and water drum 3. By 55 admitting the steam into the dry pipe, very near the ends of the rear steam and water drum, as indicated in Fig. 2, steam of the maximum dryness will be obtained should water be carried over from the middle drum 60 through the steam circulators. By raising the rear drum above the standard position, the dry pipe 24 is correspondingly raised above the water level in the rear drum and this eliminates any trouble which might 65 occur, when there is high water in the

boiler, with the rear drum at a lower level, through the water being carried along with steam into the dry pipe.

As I have eliminated, in the present construction, water circulators between the middle and rear steam and water drums, some other means must be provided to prevent direct impingement of the gases, flowing upward in the last pass, on the middle and rear steam and water drums and particularly on the butt-strap connections 29 and 30 between the shell sheet and the tube sheet of said drums. In the present form this protection is afforded by a special baffle 27 extending from the middle steam and water drum at a point below the butt-strap 29 to substantially the under side of the rear steam and water drum below the butt-strap 30. I have shown a sectional metallic baffle of cast iron, without brick protection, supported from above by rods 28. By using a baffle such as 27 there is no danger of over-heating the rear steam and water drum when the boiler is run at high ratings and the water level falls in the rear drum. The baffle 27 also prevents over-heating at the butt-straps 29 and 30.

What I claim and desire to secure by Letters Patent of the United States is:—

1. A steam boiler of the class described comprising at least three upper transverse drums connected by banks of tubes to a lower water chamber, the rear upper drum being set at a higher level than the front upper drum, a feed water inlet leading into the rear upper drum, a main steam offtake leading from said rear drum, baffles for directing the gases over and among the tubes of said banks with an up-pass in the rear bank, and a special baffle extending rearwardly from the middle upper drum and arranged to direct the gases leaving the upper part of the rear bank so as to protect the middle and rear drums from excessive heating.

2. A steam boiler of the class described comprising at least three upper transverse drums connected by banks of tubes to a lower water chamber, the middle and rear upper drums being set at substantially the same level and at a higher level than the front upper drum, a feed water inlet leading into the rear upper drum, a main steam offtake leading from said rear drum, baffles for directing the gases over and among the tubes of said banks with an up-pass in the rear bank, and a special baffle extending rearwardly from the middle upper drum and arranged to direct the gases leaving the upper part of the rear bank so as to protect the middle and rear drums from excessive heating.

3. A steam boiler of the class described comprising at least three upper transverse drums connected by banks of tubes to a

- lower water chamber, the rear upper drum being at substantially the same level as the middle upper drum, a feed water inlet leading into the rear upper drum, a main steam offtake leading from said rear drum, baffles for directing the gases over and among the tubes of said banks with an up-pass in the rear bank, and a special baffle extending rearwardly from the middle upper drum 5 and arranged to direct the gases leaving the upper part of the rear bank so as to protect the middle and rear drums from excessive heating.
4. A steam boiler of the class described comprising at least three upper transverse drums connected by banks of tubes to a lower water chamber, the rear upper drum being set at a higher lever than the front upper drum, a feed water inlet leading into the rear upper drum, a main steam offtake leading from said rear drum, water circulators connecting the water spaces of the front and middle drums, baffles for directing the gases over and among the tubes of 10 said banks with an up-pass in the rear bank, and a special baffle extending rearwardly from the middle upper drum and arranged to direct the gases leaving the upper part of the rear bank so as to protect the middle and rear drums from excessive heating.
5. A steam boiler of the class described comprising at least three upper transverse drums connected by banks of tubes to a lower water chamber, a dry pipe in the rear upper drum, said dry pipe having steam inlet openings near the ends thereof, a main 15 steam outlet connected to said dry pipe, and steam circulators extending from near the ends of the middle steam and water drum to the center portion of the rear upper drum. 40
6. A steam boiler of the class described comprising at least three upper transverse steam and water drums connected by banks of tubes to a lower water chamber, the rear steam and water drum being set at as high 45 a level as the middle steam and water drum, a feed water inlet leading into the rear drum, a dry pipe in said rear drum and a main steam offtake leading from said dry pipe, said dry pipe having steam inlet openings near the ends thereof, and steam circulators extending from the ends of the middle steam and water drum to about the center of the rear steam and water drum. 50
7. A steam boiler of the class described comprising at least three upper transverse drums connected by banks of tubes to a lower water chamber, the rear upper drum being set at a higher level than the front upper drum, a main steam offtake leading from said rear drum, baffles for directing gases over and among the tubes of said banks with an up-pass in the rear bank, and means to protect the middle and rear drums from excessive heating. 55
